UNITED STATES PATENT OFFICE

124,506

DESIGN FOR A DRESS

Louise Mulligan, Webster Groves, Mo.

Application October 26, 1940, Serial No. 96,096

Term of patent 3½ years

To all whom it may concern:

Be it known that I, Louise Mulligan, a citizen of the United States, residing at 23 Glen Oak Place, Webster Groves, in the county of St. Louis and State of Missouri, have invented a new, original, and ornamental Design for a Dress, of which the following is a specification, reference being had to the accompanying drawing, forming part thereof.

I claim:

The ornamental design for a dress, substantially as shown and described.

LOUISE MULLIGAN.
